(57) **CLAIM**

The ornamental design for sleek amplifier case, as shown and described.

DESCRIPTION

FIG. 1 is a top, front, and left side isometric view of a sleek amplifier case showing my design.

FIG. 2 is a front view thereof.

FIG. 3 is a left side view thereof.

FIG. 4 is a right side view thereof.

FIG. 5 is a rear view thereof.

FIG. 6 is a top view thereof; and,

FIG. 7 is a bottom view thereof.

The shading shown on the rear portion of the claimed design represents a contrasting surface.
